UNITED STATES PATENT OFFICE.

CHARLES E. THOMPSON, OF DENVER, COLORADO, ASSIGNOR TO THE MINE & SMELTER SUPPLY COMPANY, OF DENVER, COLORADO, A CORPORATION OF COLORADO.

TABLE-TILTING MECHANISM.

1,399,091.

Specification of Letters Patent.

Patented Dec. 6, 1921.

Application filed May 15, 1919. Serial No. 297,198.

To all whom it may concern:

Be it known that I, CHARLES E. THOMPSON, a citizen of the United States, residing at the city and county of Denver, and 5 State of Colorado, have invented certain new and useful Improvements in Table-Tilting Mechanism, of which the following is a specification.

This invention relates to an improvement 10 in table tilting mechanism.

This improved tilting device is a simple and unique feature. By this arrangement, it is possible to do away with all wedges, cams, tilting yokes, etc., such as have been 15 previously used in other concentrator tables. The draw-bar employed is so designed as to enable the deck to be tilted without putting any side strain on the yoke and working parts of the head-motion. The new design 20 makes it possible to tilt the deck by means connected with the long deck draw-bar, tube or pipe.

With these objects in view, this present invention comprises a draw-bar secured to 25 the concentrator deck or table, in connection with a suitable support for the table or deck, and means for rocking the draw-bar axially to tilt the table and for securing it in its tilted position.

30 In the accompanying drawings:—

Figure 1 is a view of the concentrator table in side elevation;

Fig. 2 is a section on line A—A of Fig. 1;

Fig. 3 is an end view showing the tilting 35 mechanism;

Fig. 4 is a plan view of the draw-bar and connected parts;

Fig. 5 is a view of the same in elevation;

Fig. 5^a is an end view of the same; 40 Fig. 6 is an end view of the tilting mechanism corresponding somewhat to Fig. 3 but on an enlarged scale;

Fig. 7 is an enlarged sectional fragmentary view of the draw-bar and its connections.

The numeral 1 represents a base, and the main frame of the machine comprises the longitudinal channel-iron sills 2 bolted to the base, and the cross channel-iron beams 50 3 bolted to the upper edges of the sills 2 in pairs, (as shown in Fig. 1) and between which are preferably located the rocker-bearings R, upon which the deck or table is supported.

55 The numeral 4 represents the deck ribs

on which the deck or table 5 is mounted. The long deck draw-bar, tube or pipe 6 extends nearly the length of the deck. This draw-bar 6 lies in a central position under the deck of the table, and is securely attached thereto by deck-ribs 7. Also attached to this long draw-bar 6 are tube brackets 8, which bolt directly to the rocker-plate 9, which is also centrally placed and supported by the main table frame or foundation. At the opposite end on the long draw-bar 6 from the head motion, a tilting-arm 10 is securely attached by pin or bolt. The end of this arm 10 fits loosely into a pocket 15 in slide-block 11, which latter is 60 made to slide back and forth on a slide-bar 12 securely bolted to the sills 2 (as shown in Fig. 6) all of which is accomplished by turning the hand-wheel 13 on the threaded rod 14, the threads of which turn in a 65 threaded hole in the slide-block, thus moving the latter transversely of the bed on the slide-rod 12, thereby moving the tilting-arm 10 to the right or left, and with it rocking the draw-bar axially, which in turn 70 tilts the deck or table to the required inclination and holds it there. The pocket 15 in the slide-block affords clearance for the tilting-arm to play back and forth as the table is reciprocated by the head-motion. 75

The draw-bar 6 is so designed and constructed that it enables the deck or table to be tilted without putting any side strain on the yoke or other working parts of the head motion. And this is accomplished by 80 means of a threaded steel rod 16, one end of which has right-hand threads 17 (see Fig. 7), and turns as the table tilts in the brass sleeve nut 18. The other end of the steel rod 16 is provided with a left-hand thread 85 19, and is locked by two steel nuts 20 and 21, the nut 21 being internally threaded for connection to the long deck draw-bar, pipe or tube 6. The brass sleeve nut 18 is also threaded to receive a steel hexagonal nut 100 22, which locks the brass sleeve nut 18 securely to the thrust-yoke 23 on the head motion. So while the draw-bar is rigidly attached to the table or deck, it is axially swiveled to the thrust-yoke of the head-motion through the right-hand screw-threads 17, which come into play as the table is transversely tilted and adjusted to get the required side slope or inclination. 105

Thus the draw-bar is of a construction to 110

permit the deck to be tilted, without putting any strain whatever on the head motion and its parts, and this improved tilting mechanism admits of the tilting of the deck without the use of cams, wedges, tilting-yokes, or other similar devices.

I claim:

1. The combination with a main frame, a table or deck and rockers interposed between 10 the two forming a movable support for the deck or table, of a draw-bar connected to the deck or table and to the rocker-bearings and having swivel connection with the head motion, adjusting means connected with the 15 draw-bar for rocking the latter axially to tilt the deck or table to the desired inclination, said tilting mechanism comprising a tilting-arm secured to the draw-bar, a sliding-block having a pocket therein which 20 receives and affords clearance for the tilting-arm as the table is reciprocated, and means for adjusting the sliding-block laterally to tilt the arm and rock the draw-bar, said means comprising a threaded rod, the 25 threads of which turn in a threaded hole in the slide block, and when turned cause the latter to slide in one direction or the other to apply lateral pressure to the tilting-arm

to tilt the latter and rock and adjust the draw-bar.

2. The combination with a draw-bar which 30 consists in the main of a pipe, a rod, means for securing the pipe and rod together, the rod having right and left threads at its opposite ends, a sleeve-nut in which one of the 35 threaded ends of the rod is swiveled, and means for securing the sleeve-nut to the thrust-yoke of the head motion of the concentrator, of tilting-mechanism comprising a tilting arm secured to the pipe, a slide 40 bar, a slide-block mounted on the slide bar and having a pocket therein which receives and forms clearance for the tilting-arm and permits the latter to slide with the reciprocation of the draw-bar, and a threaded rod 45 rotatably mounted in the main frame or bed and having a hand-wheel thereon, the threads of which engage and operate in connection with a threaded hole in the slide-block, whereby to move the latter back and 50 forth on the slide-bar when the rod is turned to rock the draw-bar axially and tilt the deck or table to the desired inclination.

In testimony whereof I affix my signature.

CHARLES E. THOMPSON
